(57) CLAIM

The ornamental design for a perfume bottle, as shown and described.

DESCRIPTION

1. Perfume bottle

1.1 : Perspective

1.2 : Front

1.3 : Back

1.4 : Right

1.5 : Left

1.6 : Top

1.7 : Bottom

Bottle comprising a body and a cap; the body is cylindrical with a circular base; it has a bottom bulging inwards; it is surmounted by a central neck in the shape of a domed ring, with a narrowing between it and an upper shoulder of the body; the cap is cylindrical with a circular base, with a diameter approximately equal to that of the narrowing of the body.
